UNITED STATES PATENT OFFICE.

JAMES B. ALLEN, OF DETROIT, MICHIGAN, ASSIGNOR TO AMERICAN TYPOGRAPH COMPANY, OF DETROIT, MICHIGAN, A CORPORATION OF MICHIGAN.

PERFORATING-MACHINE.

SPECIFICATION forming part of Letters Patent No. 764,098, dated July 5, 1904.

Application filed December 26, 1902. Serial No. 136,554. (No model.)

To all whom it may concern:

Be it known that I, JAMES B. ALLEN, a citizen of the United States of America, residing at Detroit, in the county of Wayne and State of Michigan, have invented certain new and useful Improvements in Perforating-Machines, of which the following is a specification, reference being had therein to the accompanying drawings.

10 This invention relates to improvements in perforating-machines; and its object is to provide a foot-power machine the operating-levers of which are so arranged as to give a maximum amount of power with the expenditure of a minimum amount of force and are so mounted upon the frame as to greatly reduce the liability of breaking the frame.

It is also an object of this invention to provide a machine adapted to perforate sheets of 20 any size and to so construct the die-casings that they may be easily and quickly adjusted to change the spacing of the holes to be punched or removed and others carrying dies and punches of a different size inserted.

25 A further object of the invention is to provide the machine with a cheap construction of punch and with certain other new and useful features, all as hereinafter more fully described, and particularly pointed out in the 30 claims, reference being had to the accompanying drawings, in which—

Figure 1 is a section of a device embodying my invention on the line *xx* of Fig. 2; Fig. 2, a plan view of the same with portions 35 broken away to show the construction; Fig. 3, a detail showing one of the die-casings and its supporting-bar in vertical section; Fig. 4, a detail showing the manner of securing the gage-bar to the table, and Fig. 5 is a detail 40 showing one of the punches in perspective and in an inverted position.

As shown in the drawings, 1 is the machine-frame, the end portions of which are connected at their upper ends by the two parallel 45 supporting-rods 2, upon which rods are mounted the supporting-bars 3, said rods passing through openings in the ends of the bars. Each of these bars is cut away at its upper

side to form a channel therein to receive the lower end of a die-casing 5 and within which 50 channel the casing is detachably secured by forming said channel with an undercut side 6 to engage the slanting front side of the casing and providing a wedge-block 7, having a beveled side forming an undercut to engage 55 the slanting rear side of said casing. When the block is drawn into the channel by the bolt 8 passing upward through an opening in the bar, it wedges between the rear side of the channel and the casing, and forcing the casing 60 into contact with the front undercut side of the channel firmly holds the same in place. Each casing is slotted inward from its front side at 9, and a vertical opening is formed therein above the slots to receive the punch 10, which 65 consists of a rectangular bar 11, formed with ears 12 at its upper end, between which one end of the lever 13 is pivotally secured by a pin 14, passing through the ears and through an elongated opening 15 in the end of the lever. The 70 lower end of the punch-bar 11 is provided with a rectangular groove 16, and the punch proper or head 17 is formed with a tongue 18 to project into said groove and is brazed therein, thus greatly facilitating the manufacture of 75 the punch, as the head may be accurately formed, then tempered, and quickly secured to the bar. The heads 17 may be of any desired shape to punch any form of hole, the form shown being for punching holes in the 80 leaves of loose-leaf ledgers. Secured within the lower side of the slot 9 of each casing is the die-plate 19, having an opening to fit the punch-head 17, and below the opening in the die the casing and supporting-bar 3 are each 85 formed with an opening to allow the punchings to fall through. To insure the accurate alignment of the punch with the die, the opening in the casing within which the punch moves is made somewhat larger than the 90 punch-bar, so that when the machine is set up the punch may be set loosely into the opening, with the punch-head in its die, and Babbitt metal 20 poured in around the punch-bar.

Within the rear end of each slot 9 is a stop- 95 plate 21, which forms an abutment for the

edge of the paper to determine at what distance the hole will be made from said edge, and integral with said stop 21 is an adjusting-rod 22, which extends rearwardly through an opening in the casing and is held from moving therein, when the stop is adjusted to any desired position, by a set-screw 23. On the frame are forwardly-extending integral brackets 24 to support a table 25, to each end of which table is hinged an extension-leaf 26, and in the face of the table are cut longitudinal grooves 27, extending inward from each end thereof, and over these grooves are secured plates 28, two for each slot, the adjacent edges of which are spaced apart to leave a slot in the face of the table. A gage 29 for the paper is secured to the face of the table by a bolt 30, the head of which is squared to fit the grooves 27 and the shank of which projects outward through the slot and through an opening in the gage and is provided with a thumb-nut 31 to engage the gage and bind the same. Two of these gages are used, either one of which may be readily detached, when it is desired to punch two or more holes nearer together than it is possible to place the punches, the paper being placed against the gage at one end of the table and one hole or set of holes punched, then the paper moved into engagement with the gage at the opposite end of the table to punch the adjacent hole or holes.

The punches are each actuated by one of the levers 13, which extends rearwardly some distance and is fulcrumed on the upper end of a post 32, extending upward from the supporting-bar 3, so that when power is applied to force the rear end of the lever upward the upward strain on the post, which tends to break the supporting-bar, is counteracted to some extent by the downward force of the punch.

Pivoted at its upper ends to the frame and hanging downward with its lower end adjacent to the floor is a U-shaped lever 33, provided with a treadle 34 at its lower end, and secured to its side members at a short distance from its pivots are the arms 35, which carry a cross-rod 36. Connecting-rods 37 are provided with eyes at one end to receive the rod 36, upon which they are free to move longitudinally and are pivotally connected at the opposite ends to the rear ends of the levers 13, so that when the lever 33 is swung by the foot of the operator the punch will be moved downward with great force because of the great leverage obtained by this arrangement of levers. By this arrangement very large sheets of paper may be punched, as the punches are operated by separate levers, which extend rearwardly, and there is nothing in the way at either end of the machine to prevent the paper from being inserted edge-wise into the slots of the die-casings, the paper being supported by the table, which may

be extended by raising the leaves to support large sheets.

The punches, their casings, and operating-levers are supported independently of each other by the supporting-bars, which extend in the plane of the table and are freely adjustable along the supporting-rods of the frame, the supporting-bars being held by setscrews 38 in any position to which they may be adjusted, so that the spacing of the holes may be very readily changed, and said casings being detachably secured to the supporting-bars when punches of a different size or kind are required or when they are not needed they may be quickly removed by loosening the bolts holding the wedge-blocks, removing the pin connecting the operating-levers with the punches, and slipping the casings laterally out of the channels in the bars. Any one of the punches may also be thrown out of operation by removing the pivot-pin 39, which secures the lever 13 to the post 32, and inserting this pin into holes 40, provided therefor in the side of the casing and punch-bar, the punch being thus locked within the casing and the lever allowed to rise and fall freely.

Having thus fully described my invention, what I claim is—

1. In a perforating-machine, the combination with the supporting-frame, of two parallel supporting-rods extending longitudinally of the frame, a supporting-bar supported by and movable longitudinally of the rods, a die-casing detachably secured to said bar and a die and a punch in said casing. 95

2. In a perforating-machine, the combination with the supporting-frame, of two parallel supporting-rods on the frame at its upper end, a series of supporting-bars movable longitudinally of the rods, a die-casing detachably secured to each of said bars, a die and a punch in each of said casings, an operating-lever pivoted at one end to each of the punches and fulcrumed intermediate its ends on said supporting-bar, and means for operating said levers. 105

3. In a perforating-machine, the combination with a casing and a die in said casing; of a punch-bar having a groove in its lower end, a punch-head formed to correspond with the die and provided with a tongue to engage the groove and secured therein, and means for operating said punch-bar. 115

4. In a perforating-machine, the combination with a casing provided with a rectangular guide-opening and a die in said casing below said opening, of a rectangular punch-bar guided in said opening having a slot in its lower end, a punch-head formed to correspond with the die and provided with a tongue to engage the groove in the bar, and a lever pivotally attached to the upper end of said punch-bar to operate the same. 120

5. In a perforating-machine, the combination with the supporting-frame thereof, of a 130

- series of punches adjustably supported on the frame, a series of levers supported on the frame and pivotally attached at one end to said punches, a series of connecting-rods pivotally attached to the opposite ends of said levers and provided with eyes at their opposite ends, a U-shaped lever pivoted to the frame and provided with a treadle at its lower end; and a cross-rod on said lever passing through the eyes on the connecting-rods.
6. In a perforating-machine, the combination with a supporting-frame, a series of punches mounted on said frame, and means for operating said punches; of a table supported by said frame and having a groove in its face extending inward from its end, plates secured over said groove with their adjacent edges at a distance apart to form a slot, a gage-bar, a bolt having a head to fit within said groove and extending through said slot and gage-bar, and a thumb-nut on said bolt.
7. In a perforating-machine, the combination with the frame thereof; of parallel supporting-rods secured to the frame at its upper end, supporting-bars provided with eyes to receive said rods and independently adjustable on said rods, a channel in the face of each of said bars and having an undercut side, a die-casing within each of said channels and having inclined sides and a slot extending inward from its front side, wedge-blocks, bolts to force the wedge-blocks into the channels and bind the casings therein, a die within each casing at the lower side of the slot, a vertical punch in each casing above the slot, ears on the upper ends of said punches, levers pivoted between said ears, posts on said supporting-bars to which posts the levers are pivotally attached intermediate their ends, a U-shaped lever pivoted at its upper end to the frame,
- arms on said lever, a cross-rod carried by said arms, connecting-rods having eyes to engage the cross-rod and pivoted at their opposite ends to the rear ends of the operating-levers, brackets on the frame, a table supported by said bracket, leaves hinged to the ends of said table, and a gage-bar detachably secured to the table.
8. In a perforating-machine, the combination with the supporting-frame; of a series of die-casings on said frame each provided with a die and a vertical opening above the die to receive a punch, detachable punch-bars of a diameter less than the diameter of said openings and having heads adapted to be engaged with the dies to hold the bars centered within said openings in assembling, and Babbitt metal around the punches within the openings to hold the punches square with the dies.
9. In a perforating-machine, the combination with the supporting-frame; of a series of die-casings each having a vertical opening for a punch and a small opening through its side, punches in the vertical openings in the casings and provided with small openings adapted to register with the small openings in the sides of the casing, operating-levers pivoted at one end to the upper end of the punches, posts on the frame, and detachable pivot-pins engaging openings in the levers and posts to pivotally support said levers intermediate their ends, and adapted to be inserted in the openings in the sides of the casings and punches.

In testimony whereof I affix my signature in presence of two witnesses.
